CLAIM

The ornamental design for a grip area applied to a bottle, as shown and described.

DESCRIPTION

FIG. 1 is a first front view in perspective of a grip area applied to a bottle, showing my new design;

FIG. 2 is a second front view in perspective thereof;

FIG. 3 is a rear view thereof;

FIG. 4 is a front view thereof;

FIG. 5 is a first side view thereof;

FIG. 6 is a second side view thereof;

FIG. 7 is a top view thereof; and,

FIG. 8 is a bottom view thereof.

The broken lines in each figure depict environmental subject matter that forms no part of the claimed design.

1 Claim, 7 Drawing Sheets(56)
